to The Art Metal Company, Cleveland Ohio, a
corporation of Ohio

Application March 23, 1944, Serial No. 113,013

Term of patent 14 years

(Cl. D83—1)

To all whom it may concern:

Be it known that we, George E. Glatthar and Joseph Terr, citizens of the United States and residents of University Heights and Cleveland Heights, respectively, in the county of Cuyahoga and State of Ohio, have invented a new, original, and ornamental Design for an Ultraviolet Sterilizer, of which the following is a specification, reference being had to the accompanying drawing, forming a part thereof.

In said drawing, Fig. 1 is a perspective view of an ultraviolet sterilizer showing our new design; Fig. 2 is a left end elevational view; Fig. 3 is a right-end elevational view; and Fig. 4 is a bottom plan view thereof.

We claim:

The ornamental design for an ultraviolet sterilizer, substantially as shown.

GEORGE E. GLATTHAR.
JOSEPH TERR.
